BOAT RUDDER AND REVERSIBLE PITCH PROPELLER ASSEMBLAGE

Harry G. Johnson and Leonard M. Kalous, Oshkosh, Wis., assignors to United States Motors Corporation, a corporation of Wisconsin

Application April 5, 1948, Serial No. 18,866

13 Claims. (Cl. 115—34)

1

This invention relates to improvements in boat rudder and reversible pitch propeller assemblies.

Conventional boat propelling reversible pitch propellers eliminate the need for reversing the rotation of the propeller shaft of the boat when it is desired to reverse the direction of travel of the boat, as this requirement is taken care of by reversing the pitch of the propeller blades. In such conventional reversible pitch propeller constructions a tubular propeller shaft houses a control shaft and movement of the latter operates the propeller blade pitch altering gears. In said conventional arrangement, the control shaft, housed by the driven propeller shaft, extends into the boat adjacent the operator's station. The rudder assembly is, in the conventional arrangement, entirely separate and disassociated from the reversible pitch propeller assembly.

With the foregoing in mind, a primary object of the present invention is to provide a rudder and reversible pitch propeller assembly for boats wherein the rudder shaft is operatively connected with the reversible pitch propeller in a manner so that a certain manipulation of the rudder shaft is effective to alter the pitch of the propeller blades, whereby the rudder shaft serves as the propeller blade pitch adjusting means, and the need for a control shaft extending from the propeller, through the propeller shaft, and into the boat is entirely eliminated.

A further object of the invention is to provide a boat rudder and reversible pitch propeller assembly wherein the tiller or rudder operating handle also serves as the means for adjusting the reversible pitch propeller.

A further object of the invention is to provide a rudder and reversible pitch propeller assembly which is compact and is especially suited for small inboard engine boats.

A further object of the invention is to provide a boat rudder and reversible pitch propeller assembly which permits the rudder and propeller to function in their accustomed independent manners, but which provides common adjusting means for the same.

A further object of the invention is to provide a boat rudder and reversible pitch propeller assembly with which any small inboard engine boat may be readily equipped, which is strong and durable, which is easy to manipulate, and which is well adapted for the purposes set forth.

With the above and other objects in view, the invention consists of the improved boat rudder

2

and reversible pitch propeller assembly, and its parts and combinations as set forth in the claims, and all equivalents thereof.

In the accompanying drawings in which the same reference characters indicate the same parts in all of the views:

Fig. 1 is a fragmentary longitudinal sectional view through the stern portion of a small inboard engine boat equipped with the improved rudder and reversible pitch propeller assembly;

Fig. 2 is a fragmentary rear view of the boat with the rudder and reversible pitch propeller assembly mounted thereon;

Fig. 3 is an enlarged fragmentary detail sectional view taken on line 3—3 of Fig. 1; and

Fig. 4 is an enlarged fragmentary detail sectional view taken on line 4—4 of Fig. 1.

Referring now more particularly to the drawing, it will appear that a small inboard engine boat is designated by the numeral 8. The hull of the boat, toward the stern thereof, is provided with a depending bracket 9 in which is journalled the propeller shaft 10. The latter extends to and is driven by the inboard motor (not shown) of the boat. The rear end portion of the propeller shaft 10 is connected fast to the bored hub portion 11 of a reversible pitch propeller designated generally by the numeral 12 (see Fig. 4). As is conventional with reversible pitch propellers, each of the blades 13 thereof is carried by a shank 14 which extends into openings therefor in the propeller hub 11, with the inner ends of the shanks being formed as gears 15. The gears 15 are disposed on opposite sides of and in mesh with the teeth of a rack 16. In conventional reversible pitch propeller arrangements, the rack 16 would have a shank and operating rod extending forwardly through the tubular propeller shaft 10. However, in the present invention the rack 16 is provided with a rearwardly extending shank 17 having a reduced cylindrical stem portion 17' which is revolvable within a bearing 18 in a connector 19.

The stern board 20 of the boat 8 has bolted thereto a lower bracket 21 and an upper bracket 22 which project exteriorly of the stern board of the boat and provide means for operatively mounting a rudder shaft 23.

The lower bracket 21 is of bifurcated construction, as is shown in Fig. 2, and aligned, spaced, horizontal bearing bosses 24 thereon rotatably receive the extremities of studs 25 which are integral with and project from opposite sides of a vertical sleeve 26 through which the

rudder shaft 23 revolvably extends. The lower bracket 21, therefore, constitutes a pivotal mounting for an intermediate portion of the rudder shaft 23 so that said shaft may be rocked fore and aft on a horizontal axis.

Both the lower bracket 21 and the upper bracket 22 are carried by a plate 27 with the lower bracket being secured against the plate and to the stern board 20 by bolts 28. The construction of the upper bracket 22 is shown most clearly in Fig. 3, and it will be noted that the bracket includes a T member 29, the head of which slidably engages the shank portions of elongated bolts 30 whose threaded extremities pass through the plate 27 and the stern board 20 in spaced relationship and carry clamping nuts 31. The outer extremities of the bolts 30 carry adjusting nuts 32 and lock nuts 33 which may be adjusted to regulate and limit the amount of reciprocatory movement of the T member 29 on the bolt shanks 30. Inward movement of the member 29 on the bolt shanks 30 is yieldingly resisted by coiled springs 34 confined between portions of the head of the T 29 and washers 35 seated against adjustable bolts 36 on intermediate portions of the shanks of the bolts 30. The T member 29 is formed with a sleeve portion 29' which revolvably engages the rudder shaft 23. The leg portion of the T member 29 is recessed and houses a stud 37 to which is attached one end portion of an operating cable 38. The operating cable extends movably through registering apertures therefor in the plate 27 and in the stern board 20 and is trained about suitable pulleys 39 secured to inner wall portions of the boat 8. On an inner side wall portion of the boat toward the bow thereof, is a plate 40 on which is pivotally mounted a lever 41 having attached thereto the forward end of the cable 38. Intermediately pivotally mounted on the plate 40 is a bell crank operating lever 42. The handle portion 42' thereof may be manually engaged to rock the lever and the lower angular arm portion of the lever 42, which is shouldered at its outer end, engages with a fixed pin 43 on the lever 41. Consequently, movement of the lever 42' in the proper direction is effective to exert a pull on the cable 38 which will reciprocate the T member 29 forwardly on the bolt shanks 30 against the tension of the coiled springs 34. This manipulation of the cable 38 permits the boat operator, in a forward position in the boat, to swing the rudder shaft 23 fore or aft on its pivotal mounting 25 whereby, through the connections later to be described, the pitch of the propeller blades 13 may be adjusted or varied.

Another means for operating the rudder shaft 23 is provided by a tiller 44, manipulatable by a person positioned in the stern of the boat. The upper extremity of the rudder shaft 23 has fast thereon a socket member 45 into which the inner end portion of the tiller 44 projects. The portion of the tiller 44 within the socket member 45 is provided with an annular recess 46 into which the shank portion of an adjusting bolt 47 extends, the arrangement being such that the tiller may be independently rotated within the socket 45 so as to free a locking flange 48 from the projecting upper end portion of the plate 27. Thereupon, the tiller 44 may be reciprocated forwardly and rearwardly for the purpose of pivotally swinging the rudder shaft 23 fore or aft relative to its horizontal pivotal mounting 25, such movement of the rudder

shaft being permitted by the upper bracket 22 wherein the T member 29 which engages the rudder shaft 23 is yieldingly reciprocatably movable on the bolt shanks 30. An adjusting bolt 49 on the inner end of the leg of the T member 29 limits the amount of forward movement the T member 29 may have relative to the bolt shanks. It is also evident that the tiller 44, when moved through an arc, will oscillate or turn the rudder shaft 23 in its supporting sleeves 26 and 29' to thereby turn the rudder 50 mounted on the lower end portion of the rudder shaft 23.

Rotatably enclosing the lower extremity of the rudder shaft 23 is a clevis 51 in the bifurcated portion of which is pivotally mounted on a pin 52, one end portion of a link 53. The other end portion of the link 53 is pivotally mounted, as at 54, in the bifurcated rear end portion of the connector 19. Through the connections last described, therefore, fore or aft pivotal movement imparted to the rudder shaft 23 is effective to reciprocate the link 53, the connector 19 and the rack 16, whereby the gears 14 are turned to adjust the pitch of the propeller blades 13, as desired.

From the foregoing description, it will be evident that the reversible pitch propeller 12 is driven by the propeller shaft 10. However, the means for adjusting or reversing the pitch of the propeller blades 13 is accomplished by rocking movements of the rudder shaft 23 which may be rocked through the connections previously explained by manipulation of the cable 38 or by forward and rearward movement of the tiller 44. The broken lines in Fig. 1 extending along the rudder shaft show the neutral position of the rudder shaft and the positions to affect either of the extreme pitched positions of the propeller blades 13 for forward or reverse propulsion of the boat. Through the locking flange 48 on the tiller 44, the rudder shaft may be maintained in its neutral position, but upon revolving the tiller to free the flange from the blade 27, the rudder shaft may be swung on the pivotal mounting 25 to effect the desired pitch of the propeller blades.

The assemblage is extremely compact, simple, and minimizes the parts and connections required. Also, the boat operator, seated in the stern of the boat, need only manipulate the tiller 44 to both steer the boat and to so adjust the propeller blades that the boat may be propelled forwardly or rearwardly as desired. The improved boat rudder and reversible pitch propeller assemblage is especially suited for small inboard motor boats and is well adapted for the purposes described.

What is claimed as the invention is:

1. In a boat having a reversible pitch propeller including means for adjusting the pitch of the propeller blades, a rudder shaft revolvably and pivotally mounted on the boat, an independent rudder carried by said shaft, and connections between the rudder shaft and the propeller blade adjusting means whereby pivotal movements imparted to the rudder shaft are transmitted to said propeller blade adjusting means to vary the pitch of the propeller blades.

2. In a boat having a reversible pitch propeller, a generally upright rudder shaft, a rudder carried by a lower portion of said shaft, means revolvably mounting said rudder shaft on the boat whereby the rudder may be turned for boat steering purposes, means forming a pivotal connec-

tion between an intermediate portion of the rudder shaft and the boat for rocking the rudder shaft fore and aft, and operating connections between the rudder shaft and the reversible pitch propeller whereby fore and aft rocking movements imparted to the rudder shaft are transmitted to the reversible pitch propeller for blade pitch adjusting purposes.

3. In a boat having a reversible pitch propeller, a generally upright rudder shaft revolvably and swingably mounted on the boat, a rudder carried fast by a lower portion of said shaft, means carried by said rudder shaft for selectively revolving or swinging said shaft, and connections between the rudder shaft and the reversible pitch propeller whereby swinging movements imparted to the rudder shaft are transmitted to the reversible pitch propeller for blade pitch adjusting purposes.

4. In a boat having a reversible pitch propeller, a sleeve tiltably mounted on the stern of a boat, a rudder shaft journalled in said sleeve and tiltably therewith, a rudder carried fast by a lower portion of said shaft, a tiller carried by an upper portion of said rudder shaft and manually manipulatable to revolve said shaft, said tiller also being manually manipulatable to tilt said shaft, other means extending from the rudder shaft to a more forward position in the boat for tiltably moving the rudder shaft, and operating connections between the rudder shaft and the reversible pitch propeller whereby tilting movements imparted to the rudder shaft are transmitted to the reversible pitch propeller.

5. In a boat having a reversible pitch propeller, a rudder shaft, a rudder carried by a lower portion of said shaft, a bracket having a sleeve revolvably engaging said rudder shaft and mounting the same on the boat, said sleeve being pivotally carried by the bracket, and operating connections between the rudder shaft and the reversible pitch propeller whereby pivotal movements imparted to the rudder shaft are transmitted to the reversible pitch propeller.

6. The combination with a boat propelled by a propeller having adjustable pitch blades and means associated with the propeller for mechanically adjusting the blades, of a rudder shaft turnably and pivotally mounted on the boat, a rudder fast on said rudder shaft to turn therewith, and a connection between said rudder shaft and the propeller blade adjusting means responsive to pivotal movements of the rudder shaft.

7. The combination with a boat propelled by a propeller having adjustable pitch blades and reciprocatory means associated with the propeller for mechanically adjusting the blades, of a rudder shaft turnably and pivotally mounted on the boat, a rudder fast on said rudder shaft to turn therewith, and a connection between said rudder shaft and said reciprocatory means for longitudinally moving the latter in a desired direction in response to a pivotal movement of the rudder shaft for blade adjusting purposes.

8. The combination with a boat propelled by a propeller having adjustable pitch blades and a rack mechanism for mechanically adjusting the blades, of a rudder shaft turnably and pivotally mounted on the boat, a rudder fast on said rudder shaft to turn therewith, and a connection between said rudder shaft and said rack mechanism for moving the latter in a desired direction in response to a pivotal movement of the rudder shaft for blade adjusting purposes.

9. The combination with a boat propelled by a propeller having adjustable pitch blades and a rack mechanism for mechanically adjusting the blades, of a rudder shaft, a bearing sleeve in which said shaft is journalled and reciprocatably mounted on the boat, a rudder fast on said rudder shaft to turn therewith, means fulcruming said shaft on the boat, and a connection between said rudder shaft and said rack mechanism for longitudinally moving the latter in a desired direction in response to a pivotal movement of the rudder shaft for blade adjusting purposes.

10. The combination with a boat propelled by a propeller having adjustable pitch blades and a rack mechanism for mechanically adjusting the blades, of a generally upright rudder shaft, a bearing sleeve in which said shaft is journalled, yielding means reciprocatably mounting said bearing sleeve on the stern of the boat, a rudder fast on a lower portion of said rudder shaft to turn therewith, a pivotal mounting between another portion of the rudder shaft and the stern of the boat, and a connection between a lower portion of said rudder shaft and said rack mechanism for longitudinally moving the latter in a desired direction for blade adjusting purposes in response to a pivotal movement of the rudder shaft.

11. The combination with a boat propelled by a propeller having adjustable pitch blades and a rack mechanism for mechanically adjusting the blades, of a generally upright rudder shaft, a bearing sleeve in which an upper portion of said shaft is journalled, adjustable, yielding means reciprocatably mounting said bearing sleeve on the stern of the boat, a rudder fast on a lower portion of said rudder shaft to turn therewith, a pivotal mounting between an intermediate portion of the rudder shaft and the stern of the boat below the first-mentioned mounting, and a connection between the lower end portion of said rudder shaft and said rack mechanism for longitudinally moving the latter in a desired direction for blade adjusting purposes in response to a pivotal movement of the rudder shaft.

12. The combination with a boat propelled by a propeller having adjustable pitch blades and a rack mechanism for mechanically adjusting the blades, of a rudder shaft, a bearing sleeve in which said shaft is journalled and reciprocatably mounted on the boat, a rudder fast on said rudder shaft to turn therewith, means fulcruming said shaft on the boat, a connection between said rudder shaft and said rack mechanism for longitudinally moving the latter in a desired direction in response to a pivotal movement of the rudder shaft for blade adjusting purposes, a tiller carried by the upper end portion of the rudder shaft and manipulatable to revolve the rudder shaft or to rock it on its fulcrum, and means for releasably retaining the rudder shaft in a desired position.

13. The combination with a boat propelled by a propeller having adjustable pitch blades and a rack mechanism for mechanically adjusting the blades, of a generally upright rudder shaft, a bearing sleeve in which an upper portion of said shaft is journalled, yielding means reciprocatably mounting said bearing sleeve on the stern of the boat, a rudder fast on a lower portion of said rudder shaft to turn therewith, a pivotal mounting between an intermediate portion of the rudder shaft and the stern of the boat below the first-mentioned mounting, a connection between the lower end portion of said rudder shaft and

said rack mechanism for longitudinally moving the latter in a desired direction for blade adjusting purposes in response to a pivotal movement of the rudder shaft, a tiller carried by an upper end portion of the rudder shaft for turning or pivoting the same, and an elongated connection extending from the rudder shaft to a forward position in the boat for pivotally moving the rudder shaft.

HARRY G. JOHNSON,
LEONARD M. KALOUS.
